UNITED STATES PATENT OFFICE.

JOSEPH P. VOGEL, OF PITTSBURGH, PENNSYLVANIA, ASSIGNOR TO HEYL & PATTERSON, INC., OF PITTSBURGH, PENNSYLVANIA, A CORPORATION OF PENNSYLVANIA.

PICKING TABLE.

Application filed November 24, 1919. Serial No. 340,299.

To all whom it may concern:

Be it known that I, JOSEPH P. VOGEL, a citizen of the United States, and resident of Pittsburgh, in the county of Allegheny and State of Pennsylvania, have invented a new and useful Improvement in Picking Tables; and I do hereby declare the following to be a full, clear, and exact description thereof.

10 My invention relates to picking-tables for use in connection with mining operations where the coal or other mined product has certain impurities which have to be removed before the coal is delivered into cars for 15 shipment.

The object of my invention is to provide a picking-table in which coal of different grades may be deposited on the same annular table, side by side and yet kept in 20 individual piles, and the refuse such as rock and bone picked therefrom from opposite sides and delivered by chutes to the points desired, while the picked coal is automatically discharged from the table, one grade 25 going to one point and another grade to another.

To these ends my invention comprises the novel features hereinafter set forth and claimed.

30 In the accompanying drawings, Fig. 1 is a plan view of my improved picking-table; Fig. 2 is a view partly in section of my improved table showing the manner of delivering the coal thereto and discharging it therefrom; and Fig. 3 is an enlarged cross-section on the line 3—3 of Fig. 1.

In the drawing the numeral 2 designates a suitable platform on which are mounted pedestal bearings 3 within which are 40 mounted the flanged idler-wheels 4.

The table 5 is annular in form, and secured to the bottom of said table is the annular inverted rail 6 which rests upon the treads of the idler-wheels 4.

45 The table is divided into two compartments 7 and 8 by means of the partition 9, the compartment 7 being for nut coal and the compartment 8 for lump. For convenience in picking it is desirable to have the 50 nut and lump coal separated in this manner, for it is much easier to pick out the bone and rock from coal of a certain grade than where coal of different grades are mixed together.

55 The inner and outer edges of the table

are provided with the stationary annular flanges 10.

To provide a smooth surface for the plow (hereinafter specifically referred to) to work on in the nut compartment 7 a supplemental bottom-plate 11 is provided and which does away with the obstruction which would be offered by the flange of the angle 9 forming the partition.

To provide for the rotation of the table 65 a rack 12 is secured to the lower side of the table and a driving-pinion 13 meshes with said rack, the connections between said pinion and the suitable motor being so regulated to drive the table at about 50 feet 70 per minute at its center line.

Plows 14 and 15 are provided, said plows being pivotally mounted so as to be swung into or out of position. The plow 14 is adapted to operate on the nut coal and is 75 projected into the compartment 7 while the plow 15 is adapted to act on the lump coal and is projected into the compartment 8.

A chute 16 is located in position to receive the nut coal discharged by the plow 14 and a loading boom 17 is provided to receive the lump coal from the chute 15^a plowed by plow 15 from the compartment 8 of the table. Where it is desired to deliver the 80 nut coal to the loading boom 17 for the lump coal, a fly gate 18 is provided in the nut chute 16 and by opening said gate the nut coal will be delivered by chute 18^a onto the loading boom 17 to be delivered together 85 with the lump coal at a common point.

The chutes 19 and 20 deliver the lump and nut to their respective compartments on the picking-table, the lump in the apparatus illustrated being delivered to the outside compartment and the nut to the inside 90 compartment.

The pickers stand on the inside and outside of the table and the refuse is picked and delivered into the chutes 21, said chutes communicating with a common refuse hopper, not shown.

100 By having a partition separating the lump from the nut coal on the table there is no liability of the same becoming mixed and consequently when the coal is discharged by the plows from the table the lump coal will go to the loading boom 17 while the nut coal will be discharged into the chute 16.

What I claim is:

110 1. An annular picking table, means for

- rotating same, means for delivering different grades of coal to different zones of said table, a loading boom, means for delivering coal from one of said zones to said loading boom, means for delivering the coal from the other zone in a different direction, and means for changing the means of direction of the coal from said last named zone to said loading boom.
- 10 2. An annular picking table, means for rotating the same, means for delivering different grades of coal to different zones of said table, a chute, means for discharging one grade of coal from one zone of said

table to said chute, a loading boom to receive coal from said chute, a second chute, means for discharging coal from another zone of said table on to said second chute, and a gate in said second chute whereby the material delivered to said second chute may be delivered directly on to said loading boom. 15 20

In testimony whereof I, the said JOSEPH P. VOGEL, have hereunto set my hand.

JOSEPH P. VOGEL.
